UNITED STATES PATENT OFFICE.

WALTER E. KEEBLE AND ADAM GUNSELMANN, OF TEMPLE, TEXAS.

STORM-SEWER INLET.

Application filed May 27, 1927. Serial No. 194,720.

Our invention relates to improvements in storm sewer inlets, and it consists in the combinations, constructions, and arrangements herein described and claimed.

5 An object of our invention is to provide a storm sewer inlet in which the grating is so curved as to cause trash to be washed therefrom, which would otherwise remain on the grating and clog it up if it were flat.

10 A further object is to provide a device of the type described in which the curved grating is supported by lugs carried by the frame, thus doing away with a central support and at the same time providing greater 15 strength than if the grate were flat.

15 A further object is to provide a device of the type described in which a parabolic type of curved surface grate is employed, thus providing for the same height of curb, a 20 greater clearance for the opening at the edge of the grating into the sewer, and without creating a sudden drop from the road surface or gutter onto the grating.

25 A further object of the invention is to provide a device which is built in sections and in which the end members serve for sections of greater or less length, thus obviating the necessity of duplicating parts for various sized devices.

30 Other objects and advantages will appear in the following specification, and the novel features of the invention will be particularly pointed out in the appended claims.

Our invention is illustrated in the accompanying drawings, forming part of this application, in which

Figure 1 is a perspective view of the device,

Figure 2 is a perspective view of a portion of the device as set in a curved curbing.

Figure 3 is an enlarged transverse section through a storm sewer showing the storm inlet in position, and

Figure 4 is a plan view of the frame with the grating removed.

In carrying out our invention, we make use of end members such as those shown in Figure 1. It will be seen that these end members comprise a body portion 1 having an integral upstanding portion 2 at one end thereof and an integral flange portion 3 extending substantially at right angles to the body portion. Surmounting the upstanding portions 2 is a cap portion 4 having a downwardly extending flange 5 arranged to abut the outer edge of the upstand-

ing portion 2 and having a smaller flange 6 arranged to enter a recess 7 in each of the end portions 2. This cap portion 4 has lugs 8 which lie close to the inner faces of the end portions 2 and which are secured to the end portions by means of bolts 9 and nuts 10.

60 On the side of the device next to the street is a plate 11 which has an integral flange 12 which abuts the flange 3 of each of the end members. This plate has lugs 13 similar to the lugs 8, which lie close to the inner faces of the end members 1 and are secured thereto by means of bolts 14, see Figure 4. In order to further brace the device, we provide a 70 brace rod 15 having nuts 16, between which and outer nuts 17, the end members 2 are clamped.

75 In order to support the grating 18, we provide supporting lugs 19 on the member 11 and similar lugs 20 on the end members 1.

From the foregoing description of the various parts of the device, the operation thereof may be readily understood. In Figure 3 we have shown how the storm inlet is 80 disposed with respect to the surface of the street. In this figure, the catch basin is shown at 21 and the storm sewer pipe 21', and it will be noted that the flange 12 of the member 11, as well as the flanges 3 of the end 85 members 1, are covered up with the material of the roadway 22. The upper surface 23 of the roadway is flush with the upper surface of the member 11 and also of the grating 18. The grating, it will be observed, is curved; 90 that is to say, downwardly from the street toward the opening 24 between the inner edge of the grating and the cap 4. This curvature tends to prevent the accumulation of trash on the grating which might otherwise tend to clog it and insures the sweeping away of the trash through the opening 24, which is unobstructed by cross-braces or other supports. Since the surface of the 95 roadway is on a level at 11 and since the curved surface is parabolic, the drop below the road or gutter surface is reduced to a minimum until the grating approaches the immediate front face of curb.

100 When it is desired to increase the length of the inlet, it is only necessary to provide a longer grating cap portion and portion corresponding to the member 11, the end portions being available for shorter or longer lengths, as desired.

110 We claim:

1. A storm sewer inlet, comprising a pair

- of spaced-apart end members, a plate connecting the ends of said end members, said members having integral upstanding extensions at the ends opposite said plate, a cap member for joining said extensions, and a grating supported by said end members and said connecting plate, said grating being curved downwardly from the side supported by said plate to the opposite side.
- 10 2. A storm sewer inlet, comprising a pair of end members, each of said end members having a laterally extending flange at its bottom and being provided with an upstanding portion at one end, a plate for connecting said end members at one end thereof, said plate having an outwardly extending flange at its bottom, a cap member having downwardly extending flanges arranged to fit over the upper surface of said extensions,
- 15 20 means for securing said cap member to said extension, inwardly projecting lugs carried by said end members and said plate, and a grating carried by said lugs, one side of the grating being flush with the upper surface of said plate and the ends of the grating being

flush with the upper surface of said end members, the side of said grating opposite the supporting plate terminating in a plane substantially coincident with the inner edges of said upstanding portions of the end members.

3. A storm sewer inlet, comprising end members, each of said end members having a portion provided with a curved upper surface and an integral upstanding portion having a flat top, a plate connecting the ends of the curved portion, a cap member surmounting the upper ends of said upstanding portions, means for securing said cap member to said upstanding portions, inwardly projecting lugs carried by said end members and said plate, and a grating supported upon the lugs, one side of the grating being contiguous to and flush with the upper surface of the connecting plate and the ends of the grating being contiguous to and flush with the upper curved surfaces of the end members.
